CLAIM

The ornamental design for an extrusion for base of linear lighting apparatus, as shown and described.

DESCRIPTION

FIG. 1 is a perspective view of the extrusion for base of linear lighting apparatus of the present design.

FIG. 2 is a left side elevational view, the right side elevational view being a mirror image thereof.

FIG. 3 is a top plan view.

FIG. 4 is a front elevational view, the rear elevational view being a mirror image thereof; and,

FIG. 5 is a bottom plan view.
